WINDOW STRUCTURE FOR BASEMENTS
AND THE LIKE

Forrest F. Beil and Sern Madsen, Clinton, Iowa,
assignors to Curtis Companies Incorporated,
Clinton, Iowa, a corporation of Iowa

Application September 23, 1937, Serial No. 165,366

1 Claim. (Cl. 20—42)

An object of our invention is to provide a simple and inexpensive window structure particularly adapted for a basement window, although it can be used for other installations wherever found suitable.

Another object is to provide a window structure including mounting hardware for the sash which permits the sash to move to open position with its top edge moving inwardly relative to the wall in which the window is mounted and with the bottom edge of the sash moving upwardly thus conserving head room necessary for permitting the sash to open. In this connection, the ordinary inswinging sash hinged at its top requires considerable head room for its lower edge to swing when opening the sash and such room is not always available in basements or the like used for the storage of articles.

Another object is to provide a window frame, sash, screen and hardware for the sash which all can be made and assembled at the factory and the parts of which are so related that the entire structure can be readily packaged in a carton, the hardware particularly being so designed and arranged that it does not project beyond the face of the frame and yet does not interfere with the opening action of the window or with weather stripping provided for the periphery of the sash.

A further object is to provide a window structure including a frame and a sash in the frame, mounting means being provided for the sash in the form of sliding connections and pivoted link connections, such connections being so arranged and located that they do not interfere in any way with weather stripping for the periphery of the sash and do not necessitate notching or otherwise interrupting the weather stripping.

A further object is to provide a window structure wherein the sash may be completely opened to secure full ventilation and yet the necessary head room for opening movement of the sash is comparatively small.

Still a further object is to provide a sash which may be swung inwardly, hardware being provided for mounting the sash which is entirely inward of the inner face of the sash and thereby leaves the periphery of the sash free for the application of uninterrupted weather stripping to the sides and top of the sash.

Still a further object is to provide hardware which so mounts the sash that resilient weather stripping at the sides of the sash serves as a friction means for holding the sash in various positions of open adjustment.

With these and other objects in view, our invention consists in the construction, arrangement and combination of the various parts of our window structure, whereby the objects contemplated are attained, as hereinafter more fully set forth, pointed out in our claim, and illustrated in the accompanying drawing, in which:

Figure 1 is an inside elevation of a window structure embodying our invention.

Figure 2 is a horizontal sectional view on the line 2—2 of Figure 1.

Figure 3 is a vertical sectional view on the line 3—3 of Figure 1 showing the sash in closed position by solid lines and in partly open and full open positions by dash lines and dotted lines 15 respectively.

Figure 4 is an enlarged detail sectional view on the line 4—4 of Figure 3 showing the relation of parts of the window structure with each other when the sash is fully opened; and

Figure 5 is an enlarged detail sectional view on the line 5—5 of Figure 2 showing further the relation of parts of the window structure.

On the accompanying drawing, we have used the reference numeral 10 to indicate the sill of our window frame. The side jambs thereof are indicated at 11 and the head jamb at 12. The bottom of the sill 10 and the outer surfaces of the jambs 11 and 12 are grooved as indicated at 13, 14 and 15 respectively to provide a bond between the frame and the mortar used for mounting it in a brick or masonry wall.

Within the frame formed by the members 10, 11 and 12, we provide a sash indicated generally at S. The bottom rail thereof is referred to by the reference numeral 16, the top rail by the numeral 17, the stiles by the numerals 18 and the mullions by the numerals 19.

We provide hardware for mounting the sash S for opening movement relative to the frame comprising brackets 20, 21 and 22 and links 23. The brackets 20 are angle-shaped and are mounted in a rabbet 24 along the inner corner of the head jamb 12. The brackets 21 are mounted on the stiles 18 of the sash S at substantially mid-height thereof. The links 23 have their ends pivotally connected to the brackets 20 and 21 by rivets or the like 25 and 26. On the rivets 26, friction washers 27 may be provided to aid in holding the sash in opened or partly opened position, as will hereinafter appear.

The brackets 22 are mounted on the lower rail 16 of the sash S and include pin like extensions 28. The pins 28 extend into rabbets 29 along the inner corners of the side jambs 11 and ter-

minate in grooves 30 at the bottoms of the rabbits 29. The grooves 30 extend vertically along the side jambs 11 in a plane substantially parallel to the inner face of the window frame. The pins 28 and the grooves 30 constitute guide means for the sill edge of the sash S.

The side jambs 11 and the head jamb 12 are provided with screen stops 31 and 32 respectively. A screen 33 has its frame 34 positioned against the stops 31 and 32. The upper rail of the screen has a tongue 35 adapted to fit in a groove 36 of the head jamb 12. The tongue and groove connection retains the top edge of the screen in position in the window frame. The lower edge of the screen is retained in position by a hook or catch 37. The catch 37 is pivoted at 38 to the frame 34 of the screen and is adapted to hook on a screw or the like 39 extending upwardly from the sill 10. For convenience in opening the window, a lock knob or handle 40 may be provided at its top edge.

Weather stripping W and W' extends along the sides and top of the frame. This stripping as best shown in Figure 4 is of resilient sheet metal (bronze being suitable), having a flange 41 inserted between the stops 31 and 32 and the grooves of the side and head jambs in which these stops are mounted. The weather stripping has a second flange 42 and a third flange 43.

The second and third flanges are doubled one upon the other and interposed between the jambs and the sash. They provide frictional engagement with the sash to hold it in various adjusted positions. In Figure 4 we illustrate such an engagement when the sash is in its fully opened position. Referring to Figure 3 it will be obvious, due to the type of sash hardware used, that the lower corners of the sash remain in contact with the weather stripping W throughout the entire opening movement of the sash, thus providing frictional contact to retain the sash in various open positions of adjustment without any auxiliary fastening means. This is a very desirable feature of our invention from the standpoint of operating the window, as it eliminates the necessity of manipulating any adjustable brackets or struts.

When the sash is moved to closed position the weather stripping W and W' effectively seals the sash against infiltration of air between the sash and the frame around the sides and top of the sash. The bottom rail 16 of the sash is rabbeted as indicated at 44 and a rib 45 of the sill 10 fits into this rabbet when the sash is in closed position.

An apron 46 is also mounted on the inner edge of the sill and this apron extends up slightly beyond the rabbet 44 thus providing a tortuous joint between the rail 16 of the sash and the sill of the window frame. This joint effectively reduces air and water infiltration. It is stepped

downwardly and outwardly so that any water getting into the joint, drains out on to the sloping sill.

Referring to Fig. 5, the head jamb 12 is dadoed as indicated at 47 to receive a tongue 48 of the side jamb 11 formed by rabbeting its upper end. Where the ends of the weather stripping W and W' come together, they are butt-jointed as shown. The upper outer edge of the top rail 17 of the sash is slightly rounded as indicated at 49 (see Figure 3) so that this edge when approaching closed position will engage the weather stripping W' and compress it without, however, distorting it.

We have provided a complete window structure which can be readily packaged as hereinbefore set forth and which has hardware permitting full opening of the window and thereby full ventilation through the window frame. The hardware is so mounted and the frame is so rabbeted to receive it, that the hardware in no way interferes with the application of weather stripping to the top and sides of the sash. Such weather stripping can be applied without notching or otherwise interrupting the weather stripping to accommodate brackets or other hardware members. The hardware is so designed and related to the sash and frame that the sash can swing inwardly and yet the hardware does not project beyond the inner face of the window frame. Being mounted inside, the hardware is fully protected from the weather by the weather stripping.

Some changes may be made in the construction and arrangement of the parts of our device without departing from the real spirit and purpose of our invention, and it is our intention to cover by our claims any modified forms of structure or use of mechanical equivalents which may be reasonably included within their scope.

We claim as our invention:

In a window structure, a frame including a sill, side jambs and a head jamb, a sash mounted in said frame and means for supporting the sash so that it can be opened relative to said frame comprising guide means for the sill edge of said sash, said guide means extending vertically along said side jambs and link means for said sash, said link means being pivoted to said frame adjacent the head jamb thereof and to said sash adjacent the vertical center between top and bottom thereof, and weather stripping interposed between said jambs and sash and coacting with the side edges of said sash adjacent the sill edge thereof throughout the entire movement of said sash from closed to open position, the operating parts of said guide means and said link means being entirely inside said weather stripping.

FORREST F. BEIL
SERN MADSEN.
